APPARATUS FOR THE GENERATION OF
FOAM FOR FIRE EXTINCTION

Herbert Vernon Reed, London, England

Application July 26, 1935, Serial No. 33,272
In Great Britain August 1, 1934

13 Claims. (Cl. 261—76)

This invention relates to apparatus for the generation of foam for fire extinction, in which water, air or other noninflammable gas and material such as saponin in solution are intimately mixed into a close foam, the air or other gas, and other foam forming materials being hereinafter referred to generally as foam forming substances.

In methods heretofore proposed, the intimate mixing of the water and foam forming substances has been carried out by centrifugal action, either in a bladed runner driven mechanically or by a jet of the water impinging on the blades of the runner or a separate turbine, or in a mixing channel into which the water is ejected from a turbine driving a centrifugal pump which throws the foam forming substances fed thereto by gravity into the mixing channel. There is also the known injector method of utilizing a jet of water flowing into a mixing chamber to induce into the chamber the necessary foam forming substances.

With such methods either a mechanical drive is necessary for the runner, or, if the water itself is utilized to drive the apparatus, then a considerable amount of its energy is lost, and the present invention seeks to avoid any of the known methods by providing a method wherein not only does the water induce, but positively expels, by direct impact, the foam forming substances into a mixing chamber, so that the water and foam forming substances are introduced into the said chamber separately and at such a velocity that they will be intimately mixed into a foam therein, a particular feature of this method being that the proportion of air introduced is definitely controlled. The means employed for effecting this separate and distinct introduction of the elements of the final foam, whilst deriving rotary energy from a jet of water, does so with minimum reduction of the water energy so that maximum pressure is available for expelling the foam forming substances into the mixing chamber.

The method of making foam according to the apparatus of the invention, therefore, consists in utilizing liquid pistons to induce foam forming substances into the piston cylinders which are of a predetermined and greater volume than the pistons, and at the same time to sweep out the previously induced contents of the cylinders into one part of a mixing chamber before the pistons themselves deliver into another part of the said chamber.

Thus the water and foam forming substances are kept as distinct as possible prior to delivery into the mixing chamber and due to the predeter-

mined volume of the piston cylinders a governed amount of foam forming substance—which will be principally air or may be solely air if the saponin or the like has been previously added to the water—will be introduced under pressure into the mixing chamber so as to combine therein with the water to form the foam.

The liquid pistons may be delivered on to one side of a perforated screen in the mixing chamber and the foam forming substances to the other side of the screen, but whether the screen is used or not, the pistons will always follow the foam forming substances into the mixing chamber, the foam forming substances being expelled into a part of the chamber which may circumferentially precede the part in which the pistons are delivered as in the rotary piston forming device to be described or be in line with it where a fixed piston forming device is employed as hereafter described.

The accompanying drawings illustrate various forms of apparatus for foam making according to the present invention and in these drawings:

Fig. 1 is a longitudinal cross section through apparatus employing a rotating bladed runner. 25

Fig. 2 is a front elevation of the apparatus partly in section.

Fig. 3 is a section on the line 3—3 of Fig. 1.

Fig. 4 is a developed plan of the runner and co-operating parts. 30

Figs. 5 and 6 are a plan view and a longitudinal section, respectively, illustrating an alternative form of mixing device in tube form.

Fig. 7 is a longitudinal section illustrating another alternative form of mixing device in tube form. 35

Figs. 8 and 9 are a transverse section and a side elevation, partly in section, respectively, illustrating another alternative form of mixing device. 40

In the embodiment of the invention shown in Figures 1 to 4 a cylindrical casing 1 is provided which houses a runner 2 mounted on a shaft 3 journaled in plain or ball bearings mounted in bosses 12, 13 in end plates 4, 5. 45

The runner 2 consists of external and internal shroud rings or bands 6, 7 between which are fitted blades 8 disposed obliquely to the axis of the shaft 3, the spaces between the blades opening to either side of the runner and forming passageways for the passage of liquid pistons across the runner, as will hereinafter appear. The blades 8 may alternatively be longitudinally disposed when used with an obliquely directed liquid jet, the 50

55

internal shroud 7 being suitably supported from the shaft by plates.

The front end plate 4 of the casing 1 is fitted with a water inlet 9 which may be flanged or screwed to suit any fire-hose coupling and may be perpendicular or inclined to the surface of the end plate 4. The inlet 9 is preferably of nozzle shape decreasing in area in the direction of flow so that the liquid enters the spaces between the runner blades 8 at a sufficiently high velocity.

In addition, orifices or connections 10, 11 are provided in the end plate 4 for the admission of air and saponin or the like.

The back end plate 5 has two delivery orifices 14, 15, one 14 to pass the liquid pistons and the other 15 to pass the air and saponin or the like, ejected by the pistons. Saponin or the like material may, of course, have been previously mixed with water. A long tube 16 forming a mixing chamber is attached to the end plate 5 and is divided by a perforated metal or wire mesh screen 17 into two compartments and terminates in a nozzle 18. The screen 17 may be fitted or associated with baffles 19 (see Figures 5 and 6) to ensure the passage of the liquid over the complete surface thereof so that the air delivered to the lower side of the screen is continually in contact with the liquid stream delivered to the upper side of the screen. The tube 16 may have any desired shape and in Figs. 1 and 3 is illustrated as being of substantially equal cross sectional area throughout its length, but is divided by the screen 17 so that the cross section of the air compartment gradually diminishes towards the outlet 18 while the cross section of the liquid stream compartment increases in the direction of flow so that the liquid is gradually aerated into foam. The same effect is obtained in Fig. 7 by making the perforated screen 17a conical and placing it concentrically within the mixing tube 16a, or in Fig. 6 by disposing the flat perforated screen 17b substantially parallel with the upper side of the tube 16b which increases in width in the direction of flow. A further method is to deliver the liquid tangentially to the annular space formed between two concentric cylinders 20, 21, (Figures 8 and 9) the inner one 20 of which is perforated and open to a conduit 22 to be connected to the outlet 15 of the casing through which the foam forming substances, i. e. the air and the saponin, are ejected by the liquid pistons. A conduit 24 communicates with the annular space between the cylinders, and is to be connected to the outlet 14 of the casing 1 so that the liquid pistons will be diverted spirally along the annular space between the cylinders 20, 21 by means of baffles 23, the resulting foam being collected and delivered to the nozzle 18.

The nozzle 18 and the tube 16 may be separated from the end plate 5 and connected thereto by two flexible hoses along which the separate ingredients are conveyed.

As will be seen from Figure 4, the developed shape of the runner blades is straight so that although the jet impinging thereon will cause the runner to rotate, the energy absorbed from the jet will be very small, which is unlike the usual water turbine or centrifugal pump wherein the blades are curved to absorb a considerable or the whole amount of the jet energy. The main purpose of the blades is to cut into the liquid jet and separate it into liquid pistons which are of considerably less volume than that of the spaces between the blades, and which pass with substantially the velocity of the jet along the blade

spaces thereby exhausting the spaces to allow of the free admission of air and saponin or the like thereto through the inlets 10, 11 whilst expelling by direct impact the air and saponin, previously admitted, through the outlets 14, 15, 5 the air and saponin first being expelled through outlet 15 and the pistons themselves following through the outlet 14. Thus, in the runner there is substantially no turbulence and no intimate mixing of the water and foam forming substances, 10 but instead they are kept as separate as possible within the blade spaces and only brought together in the mixing chamber, the high velocity of the various elements resulting in an intimate mixture thereof and a close foam.

It will be noted from Figure 4 that each blade space comes into register with the outlet 15 only after it has passed the inlets 10, 11, and further that it is in register with the outlet when a liquid piston commences its travel across the particular 20 space, i. e., when the latter registers with the nozzle 9. Thus the obliquity of the blades is such that a blade space, although opening on either side of the runner, never provides a direct passage between the inlets 10, 11 and the outlet 15. 25 During the passage across the runner of any liquid piston, the blade space along which it is travelling will move circumferentially so that the liquid piston passes out through the outlet 14 substantially in the original line of the jet. 30

Thus, as successive blade spaces pass the outlet 15 quantities of air will be expelled therefrom into the mixing chamber and below the screen to produce the necessary volume for foam production within the mixing chamber. The ratio 35 between a liquid piston and the volume of foam forming substance swept out thereby is definite but subject to variation by varying the ratio of the distance between blades to blade length and also by varying the inclination of the blades to 40 the runner axis.

In the above described arrangement, the liquid pistons may travel through the blade spaces during the time a space takes to travel from the commencement of outlet 15 to outlet 14; the induction action of the pistons would then be indirect, the free admission of air being due to the exhaustion of the spaces. On the other hand if the runner makes one complete revolution whilst a liquid piston is travelling through a 50 space, then as the space with the piston in it, passes the inlets 10, 11 a direct induction of the foam forming substances will occur.

I claim:—

1. Apparatus of the character described for 55 making foam for fire extinguishing, comprising a casing with a runner mounted to rotate freely therein, blades on the periphery of the runner, the spaces between the blades opening on either 60 side of the runner, a nozzle on one side of the runner for delivering a jet of liquid to the runner blades, the blades and the nozzle being disposed so that rotation of the runner is caused without substantially reducing the energy of the jet and the blades cut into the jet to form liquid 65 pistons which sweep out the spaces between the blades, inlets on the nozzle side of the runner for admitting foam forming substances to the blade spaces, and separate delivery outlets for the liquid pistons and the foam forming substances to 70 a mixing chamber on the opposite side of the runner, the outlet for the foam forming substances being arranged with respect to the inlets and the nozzle so that each blade space is in 75 register with said outlet only when the space has

passed the inlets and while a liquid piston is travelling along the particular space.

2. Apparatus for making foam for fire extinguishing comprising a casing with a runner 5 mounted to rotate freely therein, blades disposed on the periphery of the runner obliquely across the runner axis and forming straight lines when the runner is developed, the spaces between the blades opening on either side of the runner, a 10 nozzle on one side of the runner for delivering a jet of liquid to the runner blades which cut the jet into liquid pistons, an inlet on the nozzle side of the runner for admitting foam forming substances to the blade spaces and separate delivery outlets for the liquid pistons and the foam forming substances to a mixing chamber on the opposite side of the runner, the obliquity of the 15 blades being such that no direct passage is provided between the inlet and outlet of the foam 20 forming substances.

3. Apparatus of the character described, for making foam for fire extinguishing, comprising a tubular mixing chamber, a perforated screen dividing the chamber longitudinally into two 25 compartments, and means for creating liquid pistons and causing the same to deliver foam forming substances to one compartment of the mixing chamber before they themselves deliver into the other compartment of the said chamber.

30 4. Apparatus of the character described, for making foam for fire extinguishing, comprising a tubular mixing chamber of substantially constant cross section area through its length, a perforated screen dividing the chamber longitudinally into two compartments so that one of the compartments gradually diminishes in area towards the outlet end of the mixing chamber, and means for creating liquid pistons and causing same to deliver foam forming substances to the 35 compartment of gradually diminishing area before they themselves deliver into the other compartment of the mixing chamber.

5. Apparatus of the character described, for making foam for fire extinguishing, comprising a 40 cylindrical mixing chamber, a cylindrical perforated screen of smaller diameter than the chamber, and mounted concentrically therein to form two compartments, and a spiral baffle in the outer compartment formed by the space between the screen and the chamber, and means for creating liquid pistons and causing same to deliver foam forming substances to the inner compartment before they themselves deliver to the outer compartment.

55 6. Apparatus of the character described for making foam for fire extinguishing, comprising a casing having an inlet for liquid and an outlet for liquid and foam forming substances, rotary means within said casing for dividing a stream of liquid flowing therethrough into successive liquid pistons, means for the supply of foam forming substances in front of each liquid piston prior to its discharge from said casing through said outlet, and a mixing chamber disposed to receive liquid 60 and foam forming substances discharged from said casing through said outlet.

7. Apparatus as set forth in claim 6, wherein a perforated screen divides the mixing chamber into two compartments one disposed in advance 70 of the other as regards the direction of rotation of the liquid pistons within the casing so that the foam forming substances are discharged into one of said chambers in advance of the discharge of the liquid pistons into the other of said chambers.

8. In combination with apparatus according to claim 6, a perforated screen dividing the mixing chamber into two compartments, one disposed in advance of the other as regards the direction of rotation of the liquid pistons within the casing so 5 that the foam forming substances are discharged into one of said chambers in advance of the discharge of the liquid pistons into the other of said chambers, and baffles in said last mentioned chamber to deflect the liquid from side to side 10 during its passage through said chamber.

9. Apparatus of the character described, for making foam for fire extinguishing, comprising a mixing chamber, rotary means for creating successive liquid pistons and causing each to deliver 15 in front of it a quantity of air and chemical foam formant to the said chamber before itself discharging into the chamber, said means including a nozzle delivering a jet of liquid which is cut into the liquid pistons, an air inlet angularly preceding the nozzle and an inlet for chemical foam 20 formant angularly preceding the air inlet.

10. Apparatus of the character described for making foam for fire extinguishing, comprising a casing housing a liquid piston forming device 25 and a nozzle for delivering a jet of liquid to said device, said device and nozzle being mounted for relative rotation, a series of blades immovably mounted in said device and so disposed in relation to the nozzle that they cause relative rotation between themselves and the nozzle without substantially reducing the energy of the jet, whilst cutting the jet into successive liquid pistons each of which passes axially along and sweeps out the contents of a blade space before it, inlets for foam forming substances, arranged on the nozzle side of said device so that the liquid pistons moving axially along the blade spaces induce foam forming substances behind them, and a mixing chamber into which the contents of 30 the blade spaces swept out by the pistons and the pistons deliver in succession.

11. Apparatus of the character described for making foam for fire extinguishing, comprising a casing housing a liquid piston forming device 45 and a nozzle for delivering a jet of liquid to said device, said device and nozzle being mounted for relative rotation, a series of blades immovably mounted in said device and so disposed in relation to the nozzle that they cause relative rotation between themselves and the nozzle without substantially reducing the energy of the jet, whilst cutting the jet into successive liquid pistons each of which passes axially along and sweeps out the contents of a blade space before 50 it, inlets for foam forming substances, arranged on the nozzle side of said device so that the liquid pistons moving axially along the blade spaces induce foam forming substances behind them, separate delivery outlets for the liquid pistons and the foam forming substances swept out by the pistons to a mixing chamber on the opposite side of said device, the outlet for the liquid pistons being arranged in advance of the outlet for the 55 foam forming substances.

12. Apparatus of the character described for making foam for fire extinguishing, comprising a casing, a runner rotatably mounted in and about the axis of the casing, blades on the periphery of the runner extending across the casing between 60 the sides thereof in which the axis of the runner is mounted, and forming spaces open at each end, a mixing chamber having an entrance which the spaces pass in succession as the runner rotates, a nozzle for delivering a jet of liquid to the oppo- 65

site ends of the blade spaces, the blades and the nozzle being disposed so that rotation of the runner is caused without substantially reducing the energy of the jet, and the blades cut into the jet 5 to form liquid pistons which sweep out the contents of the blade spaces and then follow themselves into the mixing chamber, and inlets for admitting foam forming substances to be induced by the liquid pistons, said inlet angularly preceding the nozzle so that the foam forming substances 10 are induced into the blade spaces before the said spaces open to the entrance to the mixing chamber.

13. Apparatus of the character described for 15 making foam for fire extinguishing, comprising a casing having parallel side plates, a runner rotatably mounted between the side plates, a mixing chamber having an entrance in one side plate, blades on the periphery of the runner extending from side plate to side plate and forming spaces open at each end and successively 20

passing the entrance to the mixing chamber as the runner rotates, a nozzle attached to an inlet in the other side plate for delivering a jet of liquid to the blade spaces as they pass the inlet, the blades and the nozzle being disposed so that 5 rotation of the runner is caused without substantially reducing the energy of the jet, and the blades cut into the jet to form liquid pistons which sweep out the contents of the blade spaces and then follow themselves into the mixing 10 chamber, and an inlet for foam forming substances to be induced by the liquid pistons, said inlet being arranged in the nozzle side plate angularly before the nozzle inlet and in such a position that each blade space registers with the 15 entrance to the mixing chamber only when the space has passed the inlet for the foam forming substances, and while a liquid piston is travelling along the particular space.
